WORK HOLDER FOR BROACHING MACHINES

Oliver W. Bonnafé, Hudson, Mass., assignor to
The Lapointe Machine Tool Company, Hudson,
Mass., a corporation of Maine

Application September 11, 1941, Serial No. 410,461

12 Claims. (Cl. 90—28.1)

This invention relates to machines for broaching tubular work, such as gun barrels, and relates particularly to machines in which a plurality of broaches operate simultaneously and progressively on a plurality of work pieces.

It is the general object of my invention to provide an improved work holder for such a machine, so constructed that several work pieces may be supported therein and simultaneously advanced to successive broaching positions, and also providing intermediate broach-return positions.

A further object of my invention is to provide means to rotate each of the several work pieces about its own axis during the broaching operation and in predetermined relation to the longitudinal movement of the broaches through the work.

I also provide improved hydraulic means for intermittently advancing the work holder and for locking the work holder in broaching and in broach-return positions. Another feature of the invention relates to the provision of improved means for cooling the broaches and for lubricating the work during each broaching operation.

My invention further relates to arrangements and combinations of parts which will be herein-after described and more particularly pointed out in the appended claims.

A preferred form of the invention is shown in the drawings, in which

Fig. 1 is a sectional side elevation of the work holder, partly broken away and taken along the irregular line 1—1 in Figs. 2 and 4;

Fig. 2 is a transverse sectional elevation, taken along the line 2—2 in Fig. 1 and showing the head portion of the work holder, partially broken away;

Fig. 3 is a partial detail front elevation of the head portion, looking in the direction of the arrow 3 in Fig. 2;

Fig. 4 is a transverse sectional elevation, taken along the line 4—4 in Fig. 1 and showing the tail portion of the work holder;

Fig. 5 is a partial sectional front elevation of a broach pulling device associated with my improved work holder;

Fig. 6 is a sectional elevation of a hydraulic cylinder which operates a locking device; and

Fig. 7 is a sectional side elevation of a hydraulic cylinder and control valve which operates a feeding device.

My improved work holder comprises a head portion H and a tail portion T, both mounted on fixed guide-bars 10 (Figs. 1, 2 and 4). The head

portion H is commonly secured in fixed relation to the guide-bars 10 but the tail portion T is slidable thereon and may be secured in different longitudinal positions, which positions are determined by the lengths of the gun barrels or other work pieces to be broached.

The work holder shown in the drawings is designed to have five working positions and one loading position, equally spaced apart circumferentially, and is also provided with an intermediate broach-return position between each two work-holding or work-loading positions.

The head portion H comprises a rotary member 12 having a feed ring 18 secured to the back side thereof, as by screws 19. The ring 18 is provided with notches 20 (Fig. 2) corresponding in number and spacing to the number and spacing of the work-holding and broach-return positions. A cover plate 22 holds the member 12 and ring 18 in rotatable assembled relation in the frame 16.

Six work-holding devices are provided in the head portion H and one of these devices is shown in section in Fig. 1.

Each work-holding device comprises a hollow spindle 30 having an enlarged head 31 recessed and serrated to receive, center and grip the serrated end of a work piece W. The spindle 30 is rotatably mounted on ball bearings 32, the outer races of which are fixed in the member 12 previously described.

At its rear end, each spindle 30 is provided with a gear 33 which meshes with a pinion 35 (Fig. 2) mounted on the member 12. All of the pinions 35 are engaged and driven by a gear 37, mounted concentric with the member 12 upon ball bearings 38 and spirally grooved internally to coact with spiral splines 40 on a shaft 41. The shaft 41 is secured to the broaching head of the machine and is drawn axially through the work holder during the broaching operation but without rotation.

The broaching head and its operating means forms no part of my present invention and may be of the mechanically operated type shown at 11 in the prior patent to Bonnafé, No. 1,431,624, or of the hydraulically operated type shown at 13 in the prior patent to West, No. 1,932,760.

A plurality of broaches, corresponding in number to the broaching positions in the work holder, have their elongated shanks inserted from the left in Fig. 1 through the hollow work pieces and are secured to the broaching head, as shown in said patents. The broaches and the shaft 41 are drawn axially through the work pieces but

without rotation as the broaching head moves to the right in Fig. 1.

Such axial movement of the shaft 41 rotates the gear 37 and the movement of this gear is communicated through the pinions 35 and gears 33 to the separate work-holding devices mounted in the rotary member 12. Consequently, each work-holding device and the work mounted therein will be slowly rotated in timed relation to the longitudinal movement of the broaches, thus providing the desired lead or twist for the rifle grooves.

The tail portion T comprises a frame 50 in which a member 51 is rotatably mounted, and said member is provided with a plurality of work-engaging devices, each comprising a conically recessed work-centering device 52, slidably mounted in the hub of a spindle 53, which in turn is mounted on ball bearings 54 in the rotary member 51. Springs 55 press the devices 52 outwardly to yieldingly engage the end of the work W.

A heavy tube 60 is firmly secured by welding or otherwise to the rotary member 12 and in its left hand portion (as shown in Fig. 1) is provided with a plurality of keys 61 coacting with corresponding keyways in the rotary member 51. Consequently the tail portion T can be mounted in different axial positions on the guideways 10 but in every position the members 12 and 51 will be positively connected for simultaneous rotation.

At the intermediate or broach-return positions, openings 65 and 66 are provided in the members 12 and 51 respectively, and a guide tube 67 of suitable length is inserted in the recessed outer portions of each pair of these openings, to guide and protect the broaches during their return movement within the guide tubes. Sets of tubes 67 of different lengths are provided for different spacing of the head and tail portions.

A locking pawl 70 (Fig. 2) and a feed pawl 71 are provided in the head portion H to coact with the notches 20 in the ring 18. During a broaching operation, the locking pawl 70 occupies the position shown in Fig. 2 and firmly holds the work holder from angular displacement. When a broaching operation is completed, the locking pawl 70 is withdrawn by a hydraulically-operated piston, and the feed pawl 71 is also drawn upward preliminary to a feeding stroke. The feed pawl then moves downward, advancing the work holder $\frac{1}{2}$ of a revolution and thus bringing the broach-return tubes 67 in alignment with the broaches, which are thereupon returned through the tubes 67 to their initial positions.

As soon as the notched ring 18 begins to advance, the locking pawl 70 is released and thereafter rides on the periphery of the ring 18 until the next notch 20 comes under the pawl 70, whereupon the pawl drops into the notch and locks the ring 18 and associated parts from further movement.

The locking pawl is preferably operated by the single acting hydraulic cylinder and piston shown in Fig. 6 and comprising a piston 75 slidable in a cylinder 76 having a stop 77 to limit upward movement of the piston and also to form a guide for a spring 78. The piston 75 and associated pawl 70 are moved downward by the spring 78 to locking position, while oil under pressure from a suitable source is admitted through the connection 79 to lift the pawl preliminary to a feeding operation.

The feed pawl 71 is pivotally mounted at the

lower end of a plunger 80, slidable in a guide passage 81 in the frame member 16 of the head H. The plunger 80 is connected by a piston rod 89 to a piston 82 slidable in a cylinder 83 and connected to receive oil under pressure at either end from a supply pipe 84, and to discharge the same through an exhaust pipe 85. The direction of flow may be controlled by a rotary four-way valve 86 or in any other convenient manner.

When the valve is in the position shown in Fig. 7, the piston 82 is moved upward to withdraw the pawl 71, and when the valve position is reversed, pressure in the upper end of the cylinder 83 forces the piston 82 and pawl 71 downward to advance the rotary member 12 one space.

Special provision is made for circulating a cooling and lubricating liquid through the broaches and work pieces during the broaching operation and this construction will now be described.

In the head portion H, the spindles 30 (Fig. 1) in the work supporting devices are made hollow and the fixed frame member 16 is provided with openings 90 which are aligned with the hollow spindles 30 when the spindles are in working position. Suitable annular plates 91 and 91^a and interposed packing provide a tight joint between the spindles 30 and openings 90.

The plate 91 rotates with the work holder and has an opening for each work spindle and for each return tube. The plate 91^a is fixed to the stationary head frame member 16 and has an opening for each broaching position but no opening for loading position. This makes five openings for a six-spindle machine as shown herein.

In the tail portion T, an extension 92 (Fig. 1) is secured to the rotary member 51, as by screws 93, and this extension 92 is provided with openings 94 aligned with the work-holding devices 52 and with additional openings 95 aligned with the broach-return openings or passages 66.

Slidable bushings 97 (Fig. 1) are mounted in a fixed plate T and are adapted to be engaged by spring-pressed caps 98 (Fig. 5) mounted on the ends of broach-gripping devices 100 forming part of a puller head P. The devices 100 grip the tail shanks of the broaches as they are returned through the tubes 67. The puller head P then withdraws the broaches entirely from the work holder and later returns the broaches through the work for re-attachment to the broaching head. This return movement takes place after the work holder has advanced the work pieces to their next broaching position.

When the puller head P thus returns the broaches, the caps 98 engage the bushings 97 and force them inward against the member 92, thus closing the outer ends of the openings 94, except as they are open into the interior of the broach-gripping devices 100, which are themselves sealed to prevent leakage. The parts are retained in this position during the broaching operation.

Oil is supplied through a pipe 103, an annular channel 104 and ports 105 and 106 in the tail portion T to each work-centering device in said tail portion. Suitable valve means is to be provided for shutting off the supply of lubricant while the puller head P is removed from the sealing position shown in Fig. 5.

When the work is removed from any one of the devices 52, said device moves to the right (as seen in Fig. 1) and the oil supply for said device is thus cut off. Consequently no oil will be supplied to any work-centering device which is in loading position until the loading has been com-

pleted. The plate 91^a, as stated, has no oil opening at loading position.

The detail structure of the broach-gripping devices 100 may be substantially as shown in Fig. 5, but these devices form no part of the present invention, except as the caps 98 serve to force the bushings 97 inward and to thus close the openings 94 in the member 92 during the broaching operation.

It will thus be seen that I have provided a work holder readily adapted to receive work pieces of different lengths, to hold a plurality of work pieces in broaching position, and to permit reloading in one position while broaching operations are being performed in the remaining positions.

I have also provided means for rotating the work pieces in predetermined relation to the longitudinal movement of the broaches, through the operation of the spirally splined shaft 41, the gear 37 actuated thereby, and the gear connections to each separate work-engaging device in the head portion H.

I also provide for forced circulation of lubricant through the broaches and the work during each broaching operation, it being understood that each broach has an axial oil passage and branch openings therefrom to distribute oil along the length of the broach. This broach construction is commercial and no illustration thereof is believed necessary.

In the operation of the machine, the broaches are returned through the tubes 67 by the broaching head after a broaching operation has been completed and after the work holder has been advanced to broach-return position. The broaches are then gripped by the puller head P and are fully withdrawn from the work holder. The work holder is then advanced to the next broaching position and the puller head P returns the broaches through the work until the leading shanks of the broaches are gripped by the broaching head. The broaches are then drawn through the work pieces to perform their respective broaching operations, thus completing the working cycle.

I have thus provided an improved work holder which is particularly well adapted to the purposes for which it is designed and to the performance of the broaching operations above set forth.

Having thus described my invention and the advantages thereof, I do not wish to be limited to the details herein disclosed, otherwise than as set forth in the claims, but what I claim is:

1. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, and means to intermittently advance said work holder alternately to broaching and to broach-return positions.

2. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, and a coacting hydraulic feeding and locking mechanism by which said work holder is alternately advanced to broaching and to broach-return po-

sitions and is automatically locked in said positions.

3. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, feeding and locking means for said work holder, a double-acting hydraulic cylinder and piston to actuate said feeding means, and a single-acting hydraulic cylinder and piston with spring return to actuate said locking means.

4. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, and broach-guiding tubes connecting said head and tail portions at said intermediate positions.

5. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, and means to simultaneously rotate all of the work-engaging devices in the head portion about their separate axes and in predetermined relation to the longitudinal travel of the broaches relative thereto.

6. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, a spirally-splined device movable lengthwise with the broaches, and gear connections from said splined device to the work-engaging devices in said head portion, said connections being effective to simultaneously rotate said work-engaging devices about their own axes in predetermined relation to the longitudinal working travel of the broaches relative thereto.

7. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, a spirally-splined device movable lengthwise with the broaches, a gear in said head portion rotated by longitudinal movement of said splined device, a separate gear for each work-engaging device in the head portion, and idle pinions connecting said latter gears to said first gear for simultaneous actuation thereby.

8. In a broaching machine, a work holder comprising a head portion, a tail portion, means to hold said portions in substantially spaced relation and for simultaneous rotation, said head and tail portions each having a plurality of work-engaging devices rotatably mounted therein and having intermediate broach-return positions, and means to deliver a cooling and lubricating liquid to each broach and its associated work piece but only during a broaching operation thereon.

9. In a broaching machine, a work holder com-

prising a head portion, a tail portion, means to hold said portions in substantially spaced relation and for simultaneous rotation, said head and tail portions each having a plurality of work-engaging devices rotatably mounted therein and having intermediate broach-return positions, means to deliver a cooling and lubricating liquid to each broach and its associated work piece but only during a broaching operation thereon, and means to seal said work-engaging devices to prevent escape of liquid therefrom.

10. In a broaching machine having loading and working positions, a work holder comprising a head portion, a tail portion, means to hold said portions in substantially spaced relation and for simultaneous rotation, said head and tail portions each having a plurality of work-engaging devices rotatably mounted therein and having intermediate broach-return positions, means to deliver a cooling and lubricating liquid to each broach and its associated work piece but only during a broaching operation thereon, means to seal said work-engaging devices to prevent escape of liquid therefrom, and a fixed valve plate preventing delivery of liquid to said work-engaging devices except when said devices are in working position and are out of loading position.

11. In a broaching machine, a work holder comprising a head portion, a heavy elongated axial tube on which said head portion is secured,

a tail portion slidable on said tube but held from angular movement relative thereto, means to secure said tail portion in adjusted longitudinal position on said tube, and means to intermittently and simultaneously feed said heavy tube and said head and tail portions angularly to advance a plurality of work pieces to successive operating positions.

12. In a broaching machine, a work holder comprising a head portion, a heavy elongated axial tube on which said head portion is secured, a tail portion slidable on said tube but held from angular movement relative thereto, means to secure said tail portion in adjusted longitudinal position on said tube, means to intermittently and simultaneously feed said heavy tube and said head and tail portions angularly to advance a plurality of work pieces to successive operating positions, a spirally-splined shaft mounted within said heavy tube and slidable but non-rotatable therein, a central gear in said head portion splined to said shaft and through which said shaft is slidable, and a gear connection from said central gear to each of the work-engaging devices in said head portion, whereby said devices and the associated work pieces will be simultaneously rotated about their own axes in predetermined relation to any change in the relative axial positions of said splined shaft and work holder.

OLIVER W. BONNAFE.
